MARBLE GAME

Frederick H. King, Detroit, Mich.

Application May 17, 1944, Serial No. 535,999

3 Claims. (Cl. 273—127)

1

This invention relates to marble or ball games and particularly games the object of which is to propel marbles or the like against a pivotal target element and thereby vigorously eject a scoring or king marble carried by such element.

The improvements now made in this type of game consist primarily in adapting a bell or other sounding device to be rung by the target element when the latter is actuated with sufficient force, to mount the target element upon a frame having a portion rearward of such element serving in one position as a marble stop and in another position affording a clear passage for marbles; and to restrain the king marble from dislodgment from its seat through impact of played marbles against some portion of the frame carrying the target element.

These and various other improvements are incorporated in the game hereinafter described and illustrating in the accompanying drawings, wherein:

Fig. 1 is a perspective view of the improved game.

Fig. 2 is a rear view thereof.

Fig. 3 is a fragmentary perspective view showing the knock-down assembly of the frame parts.

Fig. 4 is a top plan view of the target member and bell.

Fig. 5 is a vertical sectional view of the target member and bell, taken on 5—5 of Fig. 2.

Fig. 6 is a fragmentary perspective view, showing a modification.

In these views, the reference character 1 designates a horizontally elongated target plate supported in an upright position by a pair of plates 2 rearwardly extending from its end portions and interconnected at their rear portions by a plate 3. The plates 1, 2, and 3 form a substantially rectangular enclosure into which marbles or the like may be propelled through an arched opening 4 rising from the lower margin of the plate 1, centrally thereof. Said plates are formed of sheet material, preferably fiber board, their interconnection being such as to afford a ready assembly and disassembly to facilitate packaging, shipment and storage of the game. Thus the plates 2 have slots 5 downwardly extended from their upper margins to receive the plates 3 and 4 and the plate 1 has slots 6 upwardly extended from its lower margin to receive the plates 2. The plate 3 is also upwardly slotted to receive the plates 2, but its portion 7 between the upward slots is best, as indicated at 8, to extend rearwardly and may alternatively have a downward inclination of about fifteen degrees as shown in

full lines in Fig. 5, or be substantially horizontal as appears in dash lines in said figure. The walls 2 are each formed on their inner faces with three protuberances 9, 10, and 11, which as clearly appears in Fig. 5, serve to hold the portion 7 in either of its two positions, the rear portions of the plates 2 being flexible slightly apart to permit swinging the portion 7 past the middle protuberances 10.

Midway between its ends, the plate 3 has a notch 12 in its upper edge, engageable by a marble-throwing target member, comprising a carrier-forming bracket and a pivotal holder and thrower for a scoring or king marble 13. Said bracket comprises an arched spring clip 14 adapted to straddle the wall 3 within the notch 12, and integrally formed at its lateral margins with a pair of spaced parallel forwardly extending metal arms 15, formed in their front portions with opposed slots 16 downwardly extended from the top edges of the arms, the lower ends of said slots being circularly enlarged as indicated at 16a. Upon and between said arms is pivoted a marble thrower formed by an elongated sheet metal strip provided remotely from its ends with a pair of oppositely laterally projecting pivot tongues 17 for engagement in the openings 16a. Rearwardly of its pivotal axis said strip is downwardly bowed to form a receiver 18 for the king marble 13, the rear end portion of said receiver extending above the walls 15 and having lateral extensions 18a to seat upon said walls under weight of the king marble. Forwardly of its pivotal axis the marble thrower forms a spring trip arm 19 having a slight forward extent from said axis and being then downwardly bent and terminating in spaced relation to the surface supporting the game. The lower end portion of the trip arm is preferably enlarged for engagement by propelled marbles. The pivot tongues 17 may extend integrally from said elongated strip but it is preferred to form said tongues on the ends of a small steel plate 19a welded to the under face of the elongated strip. The mid portions of the arms 15 have their upper margins bent slightly inward and spaced apart a distance slightly less than the diameter of the marble 13. The lips 20 thus formed safeguard the marble from ejection due to impact transmitted when the enclosure-forming frame 1, 2, 3 is struck by a propelled marble. The transmitted impact drives the marble 13 rearwardly to encounter the lips 20 which restrain further movement of the marble either rearwardly or upwardly.

From the notch 12, a slot 21 extends centrally

downward to receive a bolt 22 serving to mount a bell or other sounding device 23 on the rear face of the plate 3, such bolt passing through the clip 14 and being fastened to the latter by a nut 24. A bushing 25 on the bolt is interposed between the clip and bell to space the latter slightly from the plate 3. The opposed walls of the clip tend to spring apart divergently so that their resiliency opposes tightening of the nut 24 and has a locking effect on the tightened nut. It is apparent that the bolt 22 serves both to mount the bell and contract the clip and thus secure the target member firmly on the plate 3.

The bend 8 formed by the intersection of the plate 3 and portion 7 is interrupted midway of its length by an aperture 26 proportioned to afford contact of the enlarged end of the trip arm 19 with the bell, such contact being shown in dash lines in Fig. 5. It is to be noted that the pivot tongues 17 are positioned for insertion in the slots 16 only when the marble thrower is substantially in its limiting position illustrated by said dash line showing.

The modification shown in Fig. 6 differs from the construction already described merely in that the rear portion 7' of the plate 3' is permanently retained in its stop-forming position, a pair of opposed tongues 27 on the rear end of said portion being engaged in slots 28 in the plates 2' to maintain the portion 7' at a fixed inclination.

In playing the described game, marbles or the like are rolled or shot by the players toward the target plate, the object being to deliver the marbles through the opening 4 and against the trip arm. A certain scoring value may attach to delivery of a marble through said opening and such value may be increased by dislodging the king marble from the target member, and effecting a sounding of the bell may have a further scoring value. The maximum scoring value will derive, however, from an ejection of the king marble with sufficient force to throw it forward over the plate 4. The players may take turns in shooting one or a desired number of marbles. When the rear portion 7 is in its normal inclined position it forms a stop for marbles entering the enclosure formed by the frame, the marbles tending to wedge beneath such stop where they will not interfere with subsequent shots. If it is preferred to let the marbles pass freely through the enclosure to rebound from a wall or to be returned by one of the players, the portion 7 is adjusted to its raised position. It is further advantageous to raise the marble stop 7 when the game is positioned close to a wall, since access may then be had to any marbles underlying said marble stop by merely pulling the entire game forwardly, instead of lifting the game as would be necessary with the stop lowered.

Advantages of the game are that any desired number of players may participate, that the construction is simple, inexpensive, and easily assembled, and that it may be quite compactly packed and shipped.

What I claim is:

1. In a game, the combination with a target element having an upper marble receiver and a lower trip arm for encounter by a projectile, of a carrier for said target element having substan-

tially parallel walls between which said receiver is normally disposed, and means pivoting the target element on the carrier between the trip arm and receiver, the carrier walls being formed at their upper margins with a pair of opposed lips disposed rearwardly of the normal seating position of the marble and projecting toward each other to restrain the marble from ejection from the carrier due to an impact not acting on the trip arm.

2. A game comprising a frame having two spaced side members and a member interconnecting the side members, all of said members being formed of sheet material disposed substantially upright, the interconnecting member having its lower portion bent between the side members to extend rearwardly at a downward inclination, a target element for projectiles mounted on said interconnecting member at the front thereof and extending downwardly in front of the rearwardly bent portion of the interconnecting member, said portion being readily flexible upwardly and downwardly about its bend to assume a position in the projectile path or above such path, the side members having protuberances for retaining said bent portion in either its lowered projectile-stopping position or its raised clearance position and being resiliently flexible to permit the bent portion to pass the protuberances.

3. A game comprising a frame having two spaced side members and a member interconnecting the side members, all of said members being formed of sheet material disposed substantially upright, the interconnecting member having its lower portion being between the side members to extend rearwardly at a downward inclination, a target element for projectiles mounted on said interconnecting member at the front thereof and extending downwardly in front of the rearwardly bent portion of the interconnecting member, said portion being readily flexible upwardly and downwardly about its bend to assume a position in the projectile path or above such path, and means carried by at least one of the frame side members for limiting upward and downward swinging of said bent portion.
